UNITED STATES PATENT OFFICE.

SAMUEL P. WITHROW, OF CINCINNATI, OHIO.

BABY-CHAIR AND PERAMBULATOR.

1,155,855.

Specification of Letters Patent.

Patented Oct. 5, 1915.

Application filed November 5, 1914. Serial No. 870,507.

To all whom it may concern:

Be it known that I, SAMUEL P. WITHROW, a citizen of the United States, and residing at Cincinnati, in the county of Hamilton and State of Ohio, have invented a new and useful Improvement in Baby-Chairs and Perambulators, of which the following specification is a full disclosure.

My invention relates to a baby chair, adapted to stand upright on its base, or to be converted into a perambulator.

An object of the invention is to improve the construction and operation of the device comprising the invention of my prior patent, No. 700,397, of May 20, 1902.

The preferred embodiment of my present invention is illustrated in the accompanying drawings, forming a part of this specification, in which:—

20 Figure 1 is a side elevation of the device as a perambulator. Fig. 2 is a similar view of the device as a chair. Fig. 3 is a rear elevation of the chair. Fig. 4 is a detailed section on line 4, 4, Fig. 3, with a portion broken away to show the locking indents. Fig. 5 is a side elevation of the device as adjusted for use as a crib and showing a detachable wheel hood. Fig. 6 is a detail rear elevation of one of the wheel hoods and

30 a portion of the chair body.

The chair 1 has the seat 2, foot-rest 3 and back projections 4, enabling the chair to stand on the floor, resting upon the base provided by the bottom ends of said projections 4, and said foot-rest, as shown in Figs. 2 and 3.

40 Preferably the operative parts are all secured relative to the chair back 5, and, preferably, also, the upper portion of the chair is provided with the carrying bail 6.

To the base portion of the chair back there is secured the bearing brackets 7, 7', upon opposite sides of the chair, in which a rock shaft 8 has its bearing. Upon the ends of 45 said rock shaft, projecting beyond said bearing brackets, are secured the sheaves 9, 9'. To the outer face of each of said sheaves is secured a triangle frame 10, to the base portion 11 of which the wheels 12, 12' are attached. The triangle frame and wheels thus constitute a truck which can be swung into position above or below the chair base by reason of the pivotal connections established relative to the chair by the rock shaft and 55 sheaves. When the truck is below the base, the chair becomes a perambulator, regardless

of the angle of the chair back to the floor, while the dimension of the pivotal movement enables the truck to be swung upwardly into approximately a vertical position along side of the chair body. To the upper portion of the chair back is secured bearing brackets 13, 13', on the opposite sides of the chair, in which a rock shaft 14 has bearings, the ends of the shaft projecting 60 outwardly beyond said brackets. On the projecting ends of said shaft 14 are secured the sheaves 15, 15', and to the outer faces of said sheaves are secured the clamp sleeves 16, 16', holding the inner ends of a wheeling 65 handle 17. The sheaves 9 and 15 are connected by the belt 18, and, preferably, the respective opposite sheaves 9', 15', are connected by a belt. As indicated at 25, the ends of these belts are secured to the sheaves 70 by a wedge-shaped block, and, at 26, said belts are secured to the upper pair of sheaves to insure against belt slippage. Medially secured to the upper portion of the chair back is a bracket 19, for supporting a lock 75 mechanism consisting of rods 20, 20', aligned and spaced apart within the sleeve 19' of said bracket, the inner ends of said rods having finger grips 21, projecting through slots in the sleeve, the rods being forced 80 normally apart by a spring 22 in said sleeve. The sheaves 15, 15', are provided with a series of indents 23 upon their inner faces, adapted to be respectively aligned with the 85 ends of the locking rods when the sheaves 90 are variously adjusted.

When the device is in chair form, it may be stood on its base or carried on the arm, the wheeling handle and wheel truck being 95 relatively folded together rendering a compact structure, with no objectionable projections beyond the chair body, and, if desired, the chair body may be provided with a housing or pockets for the upwardly folded wheel truck.

To convert the chair into a perambulator, the wheeling handle is unlocked and swung upwardly, thereby swinging the wheel truck downwardly below the base, to position in which the chair stands on the wheels or becomes a perambulator. When the chair stands on this wheel base, the grip end of the wheel handle projects at an angle to the chair back at a given perpendicular distance from the floor, and any handle adjustment, 105 while the chair stands on the wheel base, serves to variously adjust the angle of the

chair back to the floor line; without varying the distance between the handle grip and the floor, by reason of the relative pivotal movements and their motion transmission connection.

5 To convert the chair into a crib, (see Fig. 5) the handle is latched with the rods 20, 20', engaging recesses 25. This will rock the wheel trucks sufficiently to allow the rear 10 pair of wheels to engage the floor, and the handle acting as a leg or brace, supports the chair in a reclining position. The wheel hoods 26 are made of woven cane or basket material suitably reinforced. The rear reinforcing strip 27 is shown as of the same 15 length as the back projections 4, which provides a wider floor contact (when used as a chair) thereby lessening the liability of upsetting.

20 The means for fastening the wheel hoods to the chair body consists of hooked projections 28, secured to the upper marginal edge of the wheel hood and a pintle 28' secured to the forward lower edge, each adapted to engage into screw eyes 29 on the chair body. The wheel hood is held in position by a plate 30, secured to the medial rear portion of the hood and secured to the chair body by a thumb nut 31. The rear of the wheel 30 hoods are open to about one-half their height to permit the wheel trucks to swing rearwardly to operative position.

35 The principle of the invention is not concerned with the number of wheels, for obviously a perambulator or a wheelbarrow nature might readily contain an embodiment of this invention, and it is also apparent that other and various changes could be made in the light of this disclosure.

40 Having thus described my invention, I claim as new and desire to secure by Letters Patent of the United States:

1. A baby chair adapted to stand on its base, a four wheel truck as a unit pivoted to 45 the lower portion of the chair and adapted to be swung to an inoperative position above the base and to a series of operative positions below the base and of variable angularity relative thereto, a wheeling handle 50 pivoted to the upper portion of the chair, and means operatively connecting said pivoted handle and truck.

2. A baby chair adapted to stand on its base, a four wheel truck as a unit pivoted to 55 the lower portion of the chair and adapted to be swung to an inoperative position above the base and to a plurality of operative positions below the base, a wheeling handle pivoted to the upper portion of the chair, 60 means operatively connecting said pivoted handle and truck, and means for locking the handle in various positions of adjustment.

3. A baby chair adapted to stand on its base, a sheave having a bearing on the lower 65 portion of the chair, a wheel truck secured

to said sheave, whereby it is movable into positions above or below the base, a sheave having a bearing at the upper portion of the chair, a wheeling handle secured to said upper sheave, and a transmitter connecting 70 said sheaves whereby the wheel truck is rendered operative or inoperative by the wheeling handle manipulation.

4. A baby chair adapted to stand on its base, a sheave having a bearing on the lower 75 portion of the chair, a wheel truck secured to said sheave, whereby it is movable into positions above or below the base, a sheave having a bearing at the upper portion of the chair, a wheeling handle secured to said upper 80 sheave, and a transmitter connecting said sheaves, whereby the wheel truck is rendered operative or inoperative by the wheeling handle manipulation, and means for locking the upper sheave in various positions of adjustment. 85

5. A baby chair adapted to stand on its base, a pivoted wheel truck, a pivoted wheeling handle, and connecting means whereby the handle manipulation renders the truck 90 operative or inoperative and determines the angular position of the chair relative to the floor when in wheeling position.

6. A baby chair adapted to stand on its base, wheels movable to an inoperative position above the base, and a plurality of operative positions below the base, a wheeling handle pivotally connected to the chair, and means connecting said pivotal portion of the handle with the wheels to render them operative or inoperative. 95

7. A baby chair adapted to stand on its base, a shaft at the lower portion of the chair, sheaves on the opposite ends of said shaft, a wheel truck fixed to said sheaves so 100 as to be movable in position above or below the base, a shaft at the upper portion of the chair, sheaves on the ends of said shaft, a wheeling handle secured to said upper 105 sheaves and motion transmission connection 110 between the upper and lower sheaves.

8. A baby chair adapted to stand on its base, a shaft at the lower portion of the chair, sheaves on the opposite ends of said shaft, a wheel truck fixed to said sheaves so 115 as to be movable in position above or below the base, a shaft at the upper portion of the chair, sheaves on the ends of said shaft, a wheeling handle secured to said upper 120 sheaves and motion transmission connection between the upper and lower sheaves, and a lock mechanism for the upper sheaves operative in predetermined positions.

9. A baby chair adapted to stand on its base, a pivoted wheel truck, a pivoted wheeling handle, motion transmission connection between the pivoted truck and handle, for swinging the truck upwardly beside the chair above the base and the handle 125 downwardly along the rear of the chair, 130

handle movement in the opposite direction swinging the truck into operative position under the base, as the handle is moved into wheeling position, and means for latching the mechanism in any one of its adjusted positions.

10. A baby chair, a wheel truck, and a wheeling handle relatively pivoted together, and operative connections between the pivotal parts, whereby the handle can be moved downwardly behind the chair back, and the truck upwardly along the side of the chair, the opposite movement bringing the truck and handle into wheeling position, 15 the handle manipulation, while in wheeling position, adjusting the angle of the chair to the floor line, while the end of the handle remains a given perpendicular distance from the floor.

20. 11. In a device of the class described comprising a chair body having a pivoted wheel truck movable to operative or inoperative positions, an operating handle therefor, and a motion transmitting device intermediate 25 the handle and truck, providing equal angular adjustment of both truck and handle from one set position to another set position.

12. A combined perambulator and chair comprising a body, a pivoted wheel truck, a 30 pivoted wheeling handle and an intermediate motion transmitting device providing equal coördinate angular adjustment of both pivoted elements relative to the chair body.

13. A combined perambulator and chair 35 comprising a body, a pivoted wheel truck, a wheeling handle pivotally journaled on the upper back portion of the body and operatively connected to the wheel truck, adapted to be folded downwardly substantially 40 parallel to the body back to position the wheel truck in inoperative position.

14. In a device of the class described comprising a wheel truck having three or more wheels, providing a definite wheel 45 base, a chair body pivoted thereon and adjustable to a series of different angular positions relative thereto, and operating means intermediate the chair body and wheel truck for adjusting the chair body relative 50 to the wheel truck.

15. In a device of the class described comprising a wheel truck having three or more wheels, providing a definite wheel base, a chair body pivoted thereon and adjustable 55 to a series of different angular positions relative thereto, said trucks being capable of adjustment to an inoperative position, and wheel hoods inclosing said truck when in inoperative position.

60. 16. In a device of the class described comprising a chair body, a pair of wheel

hoods detachably secured thereto, and a pair of wheel trucks pivotally mounted on the chair body exterior to the wheel hoods, said wheel hoods being apertured to permit the 65 wheel trucks to be swung to a concealed inoperative position within the hoods.

17. In a device of the class described comprising a pair of wheel trucks, a chair body pivoted relative thereto, and wheel 70 hoods detachably secured to the chair body, having reinforcing strips extending below the hoods and functioning in conjunction with the chair body to prevent an upsetting thereof when the device is operative as a 75 chair.

18. In a device of the class described comprising a chair body, a pair of wheel trucks pivotally mounted thereon, a pair of wheel hoods detachably secured to the chair 80 body and having a contour conforming to the radial swing of the wheel trucks and reinforcing strips for the wheel hoods extending beyond the lower marginal edge thereof functioning in conjunction with the 85 chair body to prevent an upsetting thereof when the device is converted into a chair.

19. In a device of the class described comprising a chair body, a wheel truck having three or more wheels providing a definite 90 wheel base, said truck being pivoted relative to the chair body and adjustable to an inoperative position above the chair base or an operative position below the chair base, and a protective casing or wheel hood for 95 housing the wheel truck in its inoperative position.

20. A wheel chair comprising a combined seat and back member, a wheel structure hingedly connected to said member and 100 movable to sustain said member in different position, and alternately into a non-sustaining position, and handle means for guiding the chair fixed to the back portion of 105 said member and connected with said wheel structure for moving the latter.

21. A wheel chair comprising a combined seat and back member having rigid extensions for non-motively supporting the same, a four wheel structure as a unit mounted to 110 fulcrum upon said member for motively sustaining said member, and movable into non-sustaining position, whereby said wheel structure and rigid extension may be alternately utilized for supporting said member. 115

In witness whereof, I hereunto subscribe my name, as attested by the two subscribing witnesses.

SAMUEL P. WITHROW.
